UNITED STATES PATENT OFFICE

OCTAVIO ENRIQUE MESEGUER LOPEZ, OF CAIBARIEN, CUBA

RERAILING DEVICE

Application filed April 13, 1928, Serial No. 269,792, and in Cuba April 3, 1928.

This invention relates to improvements in rerailing devices for use in returning the wheels of derailed rolling stock to the track, and has for its object to provide in connection with a device of this character means for securely anchoring the rerailing device in position with respect to the track rails during use.

With the foregoing and other objects in view the invention consists in the novel construction and arrangement of parts as hereinafter more fully described in connection with the accompanying drawing in which—

Fig. 1 is a top plan view of the rerailing device, the anchoring bolt and nut being removed;

Fig. 2 is a side elevation of the device looking in the direction of the edge which is presented to the track rail;

Fig. 3 is an elevation of the opposite side of the device;

Fig. 4 is an end elevation thereof;

Fig. 5 is a perspective view of a section of a railway track, partly broken away, showing the invention applied to use; and

Fig. 6 is a vertical transverse section, partly broken away, of a track showing the rerailing devices in use.

Referring to the drawing in detail, the numeral 1 indicates the body of the rerailing device which at its medial portion is substantially arch-shaped in section presenting a cavity 2 on its under side. From the medial arched portion of the body the upper surface thereof is sloped downwardly in opposite directions as at 3, and is provided with a curved longitudinal upright rib or flange 4 extending from one extremity thereof to the other and curving inwardly toward the central arched portion, the inclined surfaces 3 gradually diminishing in width from the extremities of the body to the medial arched portion where the rib or flange 4 merges therewith.

The side of the body 1 opposite the flange or rib 4 is of externally convexed form as at 5, gradually increasing in width from the extremities of the body to the medial portion thereof and acting to guide or deflect the

wheels A from an elevated position on to the track rails 12.

The side 7 of the body opposite the convex surface 5 is cut away as at 8 to accommodate the hand or implements employed in the setting or removal of the device in use. The relatively prominent medial portion 10 of the body is also provided with a slot 9 which may be used for the same purpose as the cut away portion 8, and in addition accommodates the shank of a bolt, as will be hereinafter more fully described.

An anchoring member 14 is provided at one extremity with a hook of such shape as to embrace the flange of the rail 12 lying opposite the flange engaged by the body 1, and as shown in Figs. 4 and 6 the under side edge of said body is recessed as at 11 to partially accommodate the last mentioned flange.

The opposite end of the anchoring member 14 is looped and receives the correspondingly shaped lower end 15' of a bolt 15 which latter passes upwardly through the slot 9 and is provided with a winged nut 17 and a washer 16.

In applying the invention to use, the body 1 is placed in the position shown in Figs. 5 and 6 with the flange of the rail base engaging in the recess 11, the anchoring member 14 being engaged with the opposite base flange and the medial or shank portion thereof facially abutting the under side of the rail base. With the parts in this position, as shown in Fig. 6, the nut 17 is turned so as to draw the bolt 15 through the slot 9, and thereby firmly draw and hold the body in position upon the rail base. The rerailing device being thus securely held in position, the wheels of the derailed car are moved upwardly along one of the inclined surfaces 3, and assume the various positions indicated in dotted lines in Figs. 5 and 6, until finally the wheels rolling upon the lateral inclination 5 move downwardly into proper position upon the track rail 12.

What I claim is:—

1. A rerailing device including a body provided with a wheel guiding upper surface and having one longitudinal edge adapted to overlie one side of the base of a rail, an an-

anchoring member having one terminal hook to embrace the opposite side of the base flange of a rail and including a shank portion adapted to facially abut the under side of a rail base, and means passing upwardly through the body and connected with the anchoring member for drawing the body firmly against a rail base.

2. A rerailing device including a body provided with a wheel guiding upper surface and having one longitudinal edge adapted to overlie one side of the base of a rail, an anchoring member having one terminal hook to embrace the opposite side of the base flange of a rail and including a shank portion adapted to facially abut the under side of a rail base, a bolt passing upwardly through the body and connected with the anchoring member, and means associated with said bolt for drawing the body against a rail base.

3. A rerailing device including a body provided with a wheel guiding upper surface and having one longitudinal edge adapted to overlie one side of the base of a rail, an anchoring member having one terminal hook to embrace the opposite side of the base flange of a rail and including a shank portion adapted to facially abut the under side of a rail base, a bolt passing vertically through the body and having its lower end loosely connected with the anchoring member, and means coacting with the bolt to draw the body firmly against a rail base.

4. A rerailing device as claimed in claim 3, characterized in that said body is provided with a slot for adjustably receiving the bolt.

5. A rerailing device as claimed in claim 3, characterized by the provision of an opening in the body elongated in the direction of the axis of the latter and permitting adjustment of the bolt and anchoring member.

In testimony whereof I affix my signature.
OCTAVIO ENRIQUE MESEGUER LOPEZ.
